UNITED STATES PATENT OFFICE.

SAMUEL E. ESTES, OF RUBY, KENTUCKY.

BRIDLE.

1,215,357.

Specification of Letters Patent. Patented Feb. 13, 1917.

Application filed August 25, 1916. Serial No. 116,840.

To all whom it may concern:

Be it known that I, SAMUEL E. ESTES, a citizen of the United States, residing at Ruby, in the county of Adair, State of Kentucky, have invented a new and useful Bridle; and I do hereby declare the following to be a full, clear, and exact description of the invention, such as will enable others skilled in the art to which it appertains to make and use the same.

This invention relates to the art of harness, and particularly to an improved and useful bridle, more especially adapted for horses of the cavalry and the like of an army.

One of the objects of the invention is to construct a bridle from a metal chain, preferably of the kind shown, and hereinafter set forth.

Another object of the invention is to provide improved means for attaching or clamping the blinds upon the opposite sides of the bridle.

In practical fields the details of construction may necessitate alterations falling within the scope of what is claimed.

The invention comprises further features and combination of parts, as hereinafter set forth, shown in the drawings and claimed.

In the drawings:

Figure 1 is a view in perspective of the improved bridle constructed in accordance with the invention.

Fig. 2 is an enlarged detail view in elevation of one side of the bridle, showing the means for attaching the blinds to the bridle.

Fig. 3 is a sectional view on line 3-3 of Fig. 2.

Fig. 4 is a detail view of the clamping plate, into which the screws carried by the blinds are threaded, for attaching the blinds to the bridle.

Fig. 5 is a detail view of the double snap hooks for attaching the ends of the sides of the bridle to the bit rings.

Referring more especially to the drawings, 1 designates a chain preferably of the kind shown, which is disposed to form the sides 2 and the head strap 3 of the bridle.

Connected to the lower end links 4 of the sides 2 of the bridle are double snap hooks 5, which in turn are connected to the bit

rings 6, to which the bit links 7 (which are linked together as at 8) are connected. A chain 9 similar to the chain 1 is turned to 55 form a loop (not shown) and has straps 10 provided with buckles 10^a connecting its end links to the bit rings, thereby providing the usual bridle reins. A chain 11 similar to the chains 1 and 9 has its end links 12 connected to the upper portions of the sides 2 of the bridle, thereby forming the usual brow band. A felt pad 3^a is disposed, as shown in dotted lines, under the head strap 3, and a felt pad 11^a, as shown in dotted lines, is disposed under the brow band 11. These two felt pads are integrally connected at 11^b, and are designed for the purpose of preventing the bridle from rubbing the horse's head and the brow thereof. The chains 13 and 14 are connected to the upper portions of the sides of the bridle adjacent where the ends of the chain 11 are connected. The chain 13 is provided with a double snap hook 15, similar to the snap hook 5, which in turn is designed to connect to the free end of the chain 14, that is when the two chains are passed under the neck of the animal, thereby providing the usual throat strap or latch. In order to shield the horse's eyes in time of 80 battle, armor plate blinds 16 are carried by the sides of the bridle, and to secure said blinds to the sides of the bridle, clamping plates 17 are provided. Each of these clamping plates or elongated strips is provided with recesses or notches 18, to receive the cross bars or rods 19 of the links of the side chains of the bridle. Each of the blinds is secured to the inner face of each side of the chain 1, there being screws 20 passing 90 through the blind and into the clamping plate or strip, as shown clearly in Fig. 3 of the drawings, thereby securely fastening the blind to the bridle, in such wise that the armor plate blind will engage the eyes of the 95 adjacent links of the sides of the bridle, thereby holding the blind securely in place.

The invention having been set forth, what is claimed as new and useful is:

In a bridle of the kind set forth, the combination of the side chains of the bridle and armor plate blinds, the links of the side chains having cross rods, of means engaging the cross rods of the links of the side chains

to secure the blinds to the sides of the bridle, said means comprising an elongated metal strip having a plurality of recesses engaging the cross rods of the links of the side chains of the bridle, and screws passing through the blind and into the strip, thereby clamping the parts together.

Copies of this patent may be obtained for five cents each, by addressing the "Commissioner of Patents, Washington, D. C."

In testimony whereof I have signed my name to this specification in the presence of two subscribing witnesses.

SAM. E. ESTES.
